WILLIAM H. WAITE, OF LYNBROOK, NEW YORK, ASSIGNOR TO DICTOGRAPH PRODUCTS COMPANY, INC., OF JAMAICA, LONG ISLAND, NEW YORK, A CORPORATION OF DELAWARE

SIGNAL SYSTEM FOR HOSPITALS

Application filed December 2, 1929. Serial No. 411,172.

This invention relates to telephonic signalling systems and has particular reference to a system having one or more master stations and a plurality of sub-stations, the sub-stations being adapted to call the master station by signalling, and the master station completing the talking circuit for oral communication, this system being particularly arranged for hospitals in such a way that the 5 master station is located in the nurse's office, and the sub-stations are located in the various patients' rooms.

Heretofore, hospitals have been equipped with visual and audible signalling systems 10 whereby the patient, upon pressing a button or other signalling device, causes the illumination of a lamp at some convenient point and/or the sounding of an audible signal in the nurse's office or the like. The nurse, upon 15 hearing and/or seeing the signal, went to the patient's room to ascertain the patient's wishes, and then went to fulfill them from materials or information readily obtainable in the nurse's office or in close proximity 20 thereto. This required at least one unnecessary trip which could be avoided had it been possible for the patient to communicate directly with the nurse in her office.

It is the principal object of this invention 25 to provide a telephonic signalling system by means of which the patient may signal to the nurse's office by operating a locking switch, thereby initiating a telephonic circuit, which is completed by the nurse in the office, so that 30 oral communication by telephone may be carried on to ascertain the patient's wishes. In this way questions may be answered and instructions given by the nurse without requiring a trip to the patient's room, and, if the 35 patient requires something, the nurse need not go to the patient's room to ascertain what is desired and then make the return trip to bring the desired articles, whereby the first 40 trip to ascertain the patient's requirements is eliminated.

Another object of this invention is to provide a system of the type described in which the apparatus is so arranged as to have the advantage of personal contact between the 45 patient and the nurse, especially in that soft

speaking instruments are provided, whereby the desired quiet and minimum of activity are obtained, and to provide a signal operable by the patient which remains in action until the nurse responds to the signal, whereby the unnecessary repetition of signals and effort on the part of the patient are eliminated.

These and other objects are obtained in a preferred embodiment of this invention 55 which includes a sub-station in each of the various patient's rooms, these sub-stations each having a signal button within convenient reach of the patient, the initial operation of which lights a door lamp above the 60 patient's door and sounds an audible signal in the nurse's office. After the patient releases the button, the audible signal in the 65 nurse's office is silenced, but the door lamp remains illuminated until the button is reset 70 after the patient's needs have been fulfilled, further operation of the button serving to again operate the audible signal in the nurse's office, but not in any way disturbing the visual signal over the patient's door.

In addition to operating an audible signal 75 and the visual signal over the patient's door, operation of the patient's button sets a visual signal in the master station in the nurse's office, this visual signal being in the form of 80 a shutter annunciator, of which one is provided for each sub-station, whereby the nurse, by glancing at the instrument, will be advised which patient is calling. By throwing a switch corresponding to the patient's 85 line as identified by the annunciator and lifting the receiver, the nurse may speak into a transmitter so that her speech is heard by the calling patient by means of a loud speaker arranged in a portable stand placed adjacent 90 the patient's bed. This portable stand is also equipped with a transmitter into which the patient may speak in response to the nurse's inquiry and carry on a conversation with the 95 nurse without effort or change in position. In the hospital ward the portable sub-station instruments are moved adjacent the occupied beds and the signal lamps are placed over the instruments so as to be readily observable by a nurse.

By means of this system a nurse can exercise aural supervision of each of the rooms without making the rounds, merely by operating the master station keys corresponding to the several patients' rooms and listening to the patients one by one. Thus, more frequent supervision is possible since by means of this system much less time is occupied and fewer personal supervisions are necessary.

10 For a better understanding of the invention, reference is made to the accompanying drawings, in which

Figure 1 is a schematic electrical diagram of the hospital telephone system of this invention; and

Fig. 2 is a schematic diagram of a modified form of reset circuit.

In these drawings, letters W, X, Y and Z designate the sub-stations in the various 20 patients' rooms in the hospital, or the several beds in a ward which is equipped with the sub-stations mentioned. Letter M designates the master station in the nurse's office to which the several sub-stations W, X, Y 25 and Z are connected.

The master station M in the nurse's office is equipped with a plurality of keys 1, 2, 3 and 4, which are respectively individual to the sub-stations W, X, Y and Z in the several 30 patients' rooms. These keys 1 to 4, inclusive, are adapted to close their corresponding contacts when the nurse in her office manipulates them in response to a signal received from the corresponding sub-stations. In 35 addition to these keys the master station has, in the best practical construction, corresponding visual signals 5, 6, 7 and 8 which also act as relays, and an audible signal 9, in the form of a make and break buzzer of the usual commercial type. The master station M also has, 40 a sensitive transmitter 10, and an ordinary watch case telephone receiver 11. The talking battery 12 and the ringing battery 13 may be provided in the master station installation or at some remote point.

The sub-stations W, X, Y and Z in the several patients' rooms include respective double signal keys 14, 15, 16 and 17, respective loud speakers 18, 19, 20 and 21, respective 50 microphone transmitters 22, 23, 24 and 25, and respective signal lamps 26, 27, 28 and 29, these signal lamps being preferably located over the door of the ward or patient's room to which they correspond so as to be 55 visible from any point in the corridor in which the particular patient's room is located, and/or on the instrument and/or over the patient's bed in a ward. In addition to these visual signals, master pilot lamps 31 60 and 31 are preferably located at the heads or intersections of the corridors, so that from a distance the nurse who is away from her office may be advised that a patient whose room is located in a particular corridor is 65 signalling.

More specifically, the patient's sub-station, say station X, includes simply the signal button 15, loud speaker 19, and transmitter or microphone 23, these instruments being preferably mounted compactly within a small cabinet adapted to be placed upon the patient's night table or in a specially constructed table. The signal button 15 may also be a separate unit on a cable within convenient reach of the patient, while the transmitter and receiver may be arranged in a cabinet in the manner described. The lamp 27 corresponding to patient's sub-station X is preferably placed over the patient's door so as to be visible from the corridor. However, when a ward is equipped with the present system, the lamp 27 may be placed over the bed of the patient having the sub-station equipment X, or the lamp 27 may be placed on the instrument stand so that the whole forms a portable 85 sub-station, the lamp 27 in either case being visible to a nurse from any part of the ward.

Similarly, the master station equipment M may be mounted in a cabinet fitted with the usual manual switches or jacks corresponding to keys 1, 2, 3 and 4, the transmitter 10, the watch case telephone receiver 11 hung upon switch hook 30 extending through the wall of the cabinet, a switch 9' for disconnecting the buzzer 9, and the annunciator relays 5, 6, 7 and 8 with their corresponding flags or shutters 32 for identifying the calling sub-station, as described in Patent No. 1,551,722, issued September 1, 1925 to F. H. N. Wohlers. The pilot lamps 31 are 100 preferably placed at the heads or intersections of corridors to advise an absent nurse from a distance that a patient is calling. These pilot lamps may be placed at any central point other than those mentioned, such as over the door of the nurse's office or the like.

Considering the electrical circuits, it will be seen that the second contacts 35 of the patients' signal buttons 14, 15, 16 and 17 are connected by the common wire 34 to the common terminal of batteries 12 and 13, and that the top contacts 33 are connected by wire 36 to the one terminal of each of the loud speakers 18, 19, 20 and 21, the respective 115 microphone transmitters 22, 23, 24 and 25, and the respective door lamps 26, 27, 28 and 29. The other terminals of the microphone transmitters 22, 23, 24 and 25 are respectively connected by wires 37, 38, 39 and 40 to the respective normally open contacts 41, 42, 43 and 44 of the respective keys 1, 2, 3 and 4 of the remote master station M in the nurse's office.

The normally open key contacts 41, 42, 43 and 44 are adapted to engage respective contacts 45, 46, 47 and 48, connected by common wire 49 to the switch hook upon which the watch case telephone receiver 11 of the master station is suspended. The telephone re-

ceiver hook, when down, provides a second break in the talking circuit, which is closed when the receiver 11 is removed, allowing the hook 30 to engage fixed contact 50 which, 5 through resistance 51, receiver 11 and wire 52, is connected to the opposite pole of talking battery 12.

It will be seen that when any one of the keys at the master station M is operated to 10 close any one of the sets of contacts 41-45, 42-46, 43-47, or 44-48, and the receiver 11 is removed from its hook, a listening circuit is completed through master station receiver 11 and any one of the patients' sub-station 15 transmitters 22, 23, 24 or 25, thus allowing master station M to listen to the patient's room, although no complete talking circuit is completed unless initiated by the patient's button.

20 The master station transmitter 10 is connected at one terminal by wire 52 and 53 to one pole of talking battery 12 and at the other terminal to the common wire 54 to which the fixed contacts 55, 56, 57 and 58 of respective master station keys 1, 2, 3 and 4 are connected. Corresponding to, but normally disengaged from, fixed contacts 55, 56, 57 and 58 are the respective contact springs 59, 60, 61 and 62, which are respectively connected 25 by wires 63, 64, 65 and 66 to the respective loud speakers 18, 19, 20 and 21 of the patients' sub-stations W, X, Y, and Z. It will be seen that when any one of the master station keys 1, 2, 3, or 4 is manipulated after a patient's contacts 33-35 have been closed in the manner described, closure of any one of the sets of contacts 55-59, 56-60, 57-61, or 58-62 completes the talking circuit 30 through the master station transmitter 10 and the corresponding one of the patients' sub-station loud speakers 18, 19, 20 or 21.

Having described the telephone circuits, the signalling circuits will now be considered. The aforementioned second contacts 45 35 of the patients' signal buttons 14, 15, 16 and 17 are adapted to be engaged by the respective top contacts 33 when the corresponding buttons are pressed. Considering that the patient in room X has pressed button 15, top contact 33 engages second contact 35 to complete a circuit from the common pole of batteries 12 and 13, wire 34, second contact 35, top contact 33, wire 36, wire 67, corresponding door lamp 27, common wire 68 to which the other door lamps 26, 28 and 29 are also connected, to the opposite pole of signal battery 13, thus illuminating lamp 27 over the signalling patient's room X. Included in this circuit are the annunciator relays 5, 6, 7 and 8 at the master station M and the master pilot lamps 31. This auxiliary circuit may be traced from signal battery 13, wire 68, wire 69, common wire 70, the windings 71, 72, 73 and 74 of respective annunciators 5, 6, 7 and 8 connected to common wire

70, respective fixed contacts 75, 76, 77 and 78 which are normally engaged by respective contact springs 59, 60, 61 and 62, respective wires 63, 64, 65 and 66, respective patients' sub-station loud speakers 18, 19, 20 and 21, top push button contacts 33, second push button contacts 35 and wire 34 to the common terminal of batteries 12 and 13.

Inasmuch as it was assumed above that the patient at sub-station X pressed the button 15, it will be seen from the auxiliary circuit just traced that relay winding 72 is energized. Relay winding 72 attracts its armature 80 to raise flag or shutter 32 to indicate that patient X is calling. When the other relay windings 71, 73 and 74 are energized, their corresponding armatures 79, 81 and 82 are attracted to display the flags 32. Adjacent relay armatures 79, 80, 81 and 82, but normally out of contact therewith are respective fixed contacts 83, 84, 85 and 86 connected to common wire 87 which leads to master pilot lamps 31 and to the common terminal of batteries 12 and 13. Thus master pilot lamps 31 are operated by the closure 90 of the relay contacts through a circuit traceable from battery 13, wires 68, 69 and 88, relay armature 80, contact 84, wire 87 and pilot lamps 31 to battery 13.

Pressure upon any one of the patients' 95 sub-station buttons 14, 15, 16 or 17 in the manner described results in the depression of second contact springs 35 to engage the bottom contact springs 90. This action has the effect of closing two switches, the first 100 switch comprising the top contact 33 and the second switch comprising the second contact 35 and bottom contact 90, second or middle contact 35 serving as the common pole for both switches as 105 it is directly connected to battery by wire 34. Again beginning with sub-station X, after the button 15 has been pressed, the circuit completed by second contact 35 and bottom contact 90 may be traced from signal 110 battery 13, wire 34, second contact spring 35, bottom contact spring 90, wire 89, buzzer disconnect switch 9', buzzer 9 and wire 69 to the opposite pole of signal battery 13. This energizes the buzzer 9, but the buzzer 115 9 is deenergizable at the master station by opening switch 9'.

After a patient has pressed a button, say button 15, a spring latch 91 holds top contact spring 33 in engagement with second 120 contact spring 35, this latch 91 having a pawl 92 under which the end of the top contact spring catches. Thus the door lamp 27 remains illuminated and the relay annunciator remains locked to display its flag 125 or shutter 32, thereby identifying in the nurse's office the particular patient who is calling or has called. These signals remain until reset by the nurse who responds to the patient's call by eventually going to the pa- 130

5 patient's room. This resetting is done by pressing the tip 93 of the latch 91 outwardly to release the end of top contact spring 33 from the latch pawl 92, whereupon the top contact 10 spring 33 breaks contact with the second contact spring 35 and the door lamp 27 is extinguished, and the annunciator 6 is deenergized to drop its flag 32 and break contact between armature 80 and contact 84, which extinguishes master pilot lamps 31. Before resetting in the manner described further pressure upon button 15 will have the effect of sounding the buzzer, because second contact 35 is then brought into engagement with 15 bottom contact 90, but the door lamp 27, master pilot lamp 31, and annunciator 32 signals are not disturbed until reset in the manner described. Thus the patient may give repeated audible signals, but the visual 20 signals 27, 31 and 32 remain set until the patient's call is answered.

25 In Fig. 2 there is illustrated a modified or auxiliary resetting device operable electrically from the nurse's office as well as mechanically in the patient's room. As shown in Fig. 1, the latch 91 catches the end of top contact spring 33 after the button 15 has been pressed to hold contact springs 33 and 35 in engagement. The latch 91 is fitted 30 with an armature 94 which cooperates with the electromagnet 95 in circuit with a battery 96 and a spring switch 97, this switch being located at the master station M. A switch 97 may be individual to each of the 35 keys 1, 2, 3 or 4, so that any one of the corresponding patients' signal buttons 14, 15, 16 or 17 may be reset after the nurse has responded telephonically to the patient's call, or a single 40 separate switch 97 at the master station M may be employed to reset all of the patients' signal buttons. It will be seen that this electromagnetic reset arrangement will not interfere with the manual reset in the patient's room, but is especially valuable when the 45 nurse does not go to the patient's room, but responds telephonically to the patient's call. There are many instances when it is not necessary for the nurse to go to the patient, but it is preferred that the patient not be allowed 50 to reset, so that the nurse must respond in any event. The signal battery 13 may also be used instead of the additional battery 96.

55 Although the operation of the telephonic signal system of this invention will be apparent to those skilled in the art from the foregoing description, the operation of the system will be briefly described in the order in which the various phases of action take place. Assuming as before that patient X presses 60 button 15 to call the nurse at master station M, top contact spring 33 engages second contact spring 35, and second contact spring 35 engages bottom contact spring 90. The engagement of contacts 33 and 35 causes the 65 lamp 27 over the patient's door to be lighted

70 and the corresponding annunciator 6 at the master station in the nurse's room to be operated to display its flag 32 and light master pilot lamps 31, thus informing the nurse that patient X is calling. Because latch 91 holds contacts 33 and 35 in engagement, door lamp 27 remains illuminated and annunciator 6 and consequently pilot lamps 31 remain operated even after the patient releases button 15. 75

The engagement of second contact 35 and bottom contact 90 closes the circuit through the buzzer 9 at the master station M if the buzzer disconnect switch 9' is closed. When patient X releases button 15, contacts 35 and 90 separate, and the buzzer is silenced, but the common side of talking battery 12 remains connected to patient's transmitter 23 and loudspeaker 19 through wire 34, contact 33, contact 35 and wire 36. 80

85 When the nurse hears the buzzer, she looks at the annunciators to ascertain which patient is calling, and, seeing annunciator 6 flag displayed, she manipulates key 2 to complete her talking circuit through patient's loud speaker 19, wire 64, contact 60, contact 56, wire 54, transmitter 10, wire 53 and wire 52 to the talking battery 12. This also resets the annunciators 6, whose circuit is broken when the key separates contacts 60 and 76. 90 This resetting of annunciator 6 also breaks the circuit through pilot lamps 31, but door lamp 27 remains illuminated because latch 91 holds contacts 33 and 35 together. If the patient keeps her finger on the button 15 or presses it insistently, the nurse may silence 95 the buzzer by opening switch 9'. After operating key 2 the nurse lifts receiver 11 from its hook, which completes the patient's talking circuit through the patient's transmitter 23, wire 38, contact 42, contact 46, wire 49, hook 30, contact 50, resistance 51, receiver 11, and wire 52 to the talking battery 12. 100

105 The nurse speaks into the transmitter 10, asking what the patient wants, and her voice issues distinctly but not loudly from the loud speaker 19 placed adjacent the patient's bed in room X. The patient, without changing position or other activity, responds, and the patient's request is transmitted by the microphone 23 to the nurse's receiver 11. After 110 ascertaining the patient's wishes, the nurse responds verbally if possible, and the call is completed, whereupon the nurse replaces the receiver 11 on the hook 30, breaking the talking circuit through the receiver 11 and patient's transmitter 23, and manipulates key 2, breaking the talking circuit through the 115 loud speaker 19 and master station transmitter 10. The nurse is then required to go to the calling patient in order to perform the service requested and to reset the locking push button by moving lever 93 outwardly to disengage the pawl 92 of latch 91 from top contact spring 33 so that the latter separates 120 from second contact spring 35. Of course, 125

if key 2 is arranged to do this resetting, it is done immediately by the nurse when the conversation with the patient has been completed, so that the nurse is not required to 5 operate lever 93 as described. It is to be noted that the nurse's local manual and the nurse's remote electromagnetic resetting acts do not interfere with each other.

If the patient asks for some article when 10 the nurse responds to the patient's call, a trip to ascertain the patient's wishes is thus saved by the nurse, and the latter may bring the article desired immediately to the patient X, resetting the button 15 by operating lever 93 15 when she reaches the patient's room, if the nurse has not already reset the button 15 magnetically from her office in the manner described.

System of this invention also provides 20 aural supervision as a valuable adjunct to the usual personal supervision and permits more frequent contacts with the patient than is possible when the nurse or supervisor must make a personal trip from one patient to the 25 other. In order to listen to each patient within a few minutes the nurse, doctor or supervisor at the master station need only place the receiver 11 to his or her ear and, by manipulating keys 1, 2, 3 and 4 successively, may 30 listen to patients W, X, Y and Z, without leaving the office.

It will be seen that this invention provides a telephonic signalling system which is especially valuable for hospitals, although it is 35 not limited to this use, and one whereby much labor is saved and a more efficient service is possible. The system may be provided with portable units so as to be readily installed and moved about, or the system may be permanently 40 installed in a hospital while it is being built or in an existing hospital without great labor or extensive alteration. Any number of sub-stations may be provided simply by duplicating the essential units, so that 45 one central station may be used to supervise an entire hospital floor of any number of rooms or a ward or wards containing any number of beds, or one master station in the hospital supervisor or superintendent's office 50 may serve all of the patients in the hospital.

While a preferred embodiment of the invention has been illustrated and described herein, it is to be understood that the invention is not in any way limited thereby, but 55 is flexible and susceptible of many alterations and changes in form and detail within its scope.

I claim:

1. In a telephone system, the combination 60 of a master station having a transmitter and receiver, a plurality of sub-stations having transmitters and receivers, a signal device at said master station and each of said sub-stations, a switch at said sub-stations for operating said signals, means for locking said

switch in operated position, and alternative means at the master station and corresponding sub-station for releasing said locking means to restore said switch.

2. In a telephone system, the combination 70 of a master station having telephone instruments, a plurality of sub-stations having telephone instruments, a switch at each sub-station for preparing a talking circuit to said master station, means at the master station for completing the talking circuit to any one of said sub-stations, a signal at the master station operable by said switch, a signal at the corresponding sub-station operable by said switch, and a signal remote 75 from the master station and the corresponding sub-station operable by said switch.

3. In a telephone system, the combination 80 of a master station having telephone instruments, a plurality of sub-stations having telephone instruments, a switch at each sub-station for preparing a talking circuit to said master station, means at the master station for completing the talking circuit to any one of said sub-stations, a signal at the master 85 station operable by said switch, and a signal remote from the master station operable by said switch.

4. In a telephone system, the combination 90 of a master station having telephone instruments, a plurality of sub-stations having telephone instruments, a switch at each sub-station for preparing a talking circuit to said master station, means at the master station for completing the talking circuit to any one of said sub-stations, a signal at the corresponding sub-station operable by said 95 switch, and a signal remote from the master station and corresponding sub-station operable by said switch.

5. In a telephone system, the combination 100 of a master station having telephone instruments, a plurality of sub-stations having telephone instruments, a switch at each sub-station for preparing a talking circuit to said master station, means at the master station for completing the talking circuit to any one of said sub-stations, a signal at the corresponding sub-station operable by said switch, and a signal remote from the master station and corresponding sub-station operable by said switch.

6. In a telephone system, the combination 110 of a master station having telephone instruments, a plurality of sub-stations having telephone instruments, a switch at each sub-station for preparing a talking circuit to said master station, means at the master station for completing the talking circuit to any one of said sub-stations, a signal remote from the corresponding sub-station operable by said switch, and a signal remote from said master station operable by said switch.

7. In a telephone system, the combination 120 of a master station having telephone instruments, a plurality of sub-stations having tele-

phone instruments, a switch at each sub-sta-
tion for preparing a talking circuit to said
master station, means at the master station
for completing the talking circuit to any one
5 of said sub-stations, and a signal remote from
said master station and substation operable
by said switch.

8. In a telephone system, the combination
of a master station having telephone instru-
10 ments, a plurality of sub-stations having tele-
phone instruments, a switch at each sub-sta-
tion for preparing a talking circuit to said
master station, means at the master station
for completing the talking circuit to any one
15 of said sub-stations, a signal at the master
station operable by said switch, and a signal
remote from said master station and sub-
stations operable by said switch.

9. In a telephone system, the combination
20 of a master station having telephone instru-
ments, a plurality of sub-stations having tele-
phone instruments, a switch at each sub-sta-
tion for preparing a talking circuit to said
master station, means at the master station
25 for completing the talking circuit to any one
of said sub-stations, a signal at the corre-
sponding sub-station operable by said switch,
and a signal remote from said sub-station op-
erable by said switch.

30 10. In a telephone system, the combination
of a master station having telephone instru-
ments, a plurality of sub-stations having tele-
phone instruments, a switch at each sub-sta-
tion for preparing a talking circuit to said
35 master station, means at the master station
for completing the talking circuit to any one
of said sub-stations, a signal at the master
station operable by said switch, a second
switch at each of the sub-stations, and a sec-
40 ond signal of different character at the mas-
ter station operable by any one of said second
switches.

45 11. In a telephone system, the combination
of a master station having telephone instru-
ments, a plurality of sub-stations having tele-
phone instruments, a switch at each sub-sta-
tion for preparing a talking circuit to said
50 master station, means at the master station
for completing the talking circuit to any one
of said sub-stations, a signal at the master
station operable by said switch, a second
switch at each of the sub-stations, a second
55 signal of different character at the master
station operable by any of said second
switches, and means at the master station for
disconnecting said second signal.

60 12. In a telephone system, the combination
of a master station having telephone instru-
ments, a plurality of sub-stations having tele-
phone instruments, a switch at each sub-sta-
tion for preparing a talking circuit to said
65 master station, means at the master station
for completing the talking circuit to any one
of said sub-stations, a signal at the master
station operable by said switch, a second

switch at each sub-station, a corresponding
signal operable thereby and means for lock-
ing one of said switches in signalling posi-
tion.

13. In a telephone system, the combination 70
of a master station having telephone instru-
ments, a plurality of sub-stations having tele-
phone instruments, a switch at each sub-sta-
tion for preparing a talking circuit to said
master station, means at the master station 75
for completing the talking circuit to any one
of said sub-stations, a signal at the master sta-
tion operable by said switch, a second switch
at each sub-station, a corresponding signal
80 operable thereby, means for locking one of
said switches in signalling position, and
means for releasing said locking means.

14. In a telephone system, the combination
of a master station having telephone instru-
85 ments, a plurality of sub-stations having tele-
phone instruments, a switch at each sub-sta-
tion for preparing a talking circuit to said
master station, means at the master station
for completing the talking circuit to any one
90 of said sub-stations, a signal at the master sta-
tion operable by said switch, a second switch
at each sub-station, a corresponding signal
operable thereby, means for locking one of
95 said switches in signalling position, electro-
magnetic means for releasing said locking
means, and a switch at said master station
for operating said electromagnetic means.

15. In a telephone system, the combination
of a master station having telephone instru-
100 ments, a plurality of sub-stations therefor
having telephone instruments, a local visual
signal for each sub-station, a visual signal
corresponding to each sub-station at said
master station, a signal remote from said
105 master and sub-stations, a switch at each sub-
station for operating the corresponding local,
remote and master station signals, a second
signal at said master station, and a second
switch at each sub-station for operating said
110 second master station signal.

16. In a telephone system, the combination
of a master station, a telephone transmitter
and receiver therefor, a plurality of sub-sta-
tions, a microphone transmitter and loud
speaker unit at each sub-station, a signal for
115 calling only said master station, and a switch
only at each of the sub-stations for preparing
a talking circuit to said master station and
for operating said master station signal, and
means only at the master station for selective-
120 ly completing the talking circuit to any one
of said sub-stations.

In testimony whereof I affix my signature.
WILLIAM H. WAITE.
